UNITED STATES PATENT OFFICE.

VICTOR THRANE, OF OSLO, NORWAY.

PROPELLING SYSTEM.

Application filed March 15, 1927, Serial No. 175,621, and in Norway March 19, 1926.

Propelling systems with movable wing surfaces have already been constructed, wherein the wings or planes are attached to a rotary drum or the like and are caused by 5 mechanical means to alter their position during the rotation in such a manner that they are exerting a propelling action in a definite direction. Usually such devices will be 10 comparatively complicated and therefore they have not obtained any practical utilization. The present invention has for its object to provide a system which is characterized substantially by this that each wing surface 15 consists of a flexible strap or ribbon stretched out between two carrying members performing an eccentric movement relatively to one another in such a manner that the distance between the carrying members and thereby the size of the wing surface is 20 subjected to periodic variations from a minimum to a maximum and back again to minimum, a suitable mechanism during this operation giving off the necessary and taking up the superfluous strap length so as to 25 maintain the strap at any time stretched to the necessary degree between the carrying members.

ner members 6 are also evenly distributed around the pivot 4. The inner carrying members do not receive a special driving but are dragged along automatically, being 60 taken along by the endless strap 7. This strap is passed in zigzag folds from one of the outer carrying members 3 inwards around an inner carrying member 6, therefrom again outwards and around the next 65 outer carrying member 3, then inwards and around the next inner carrying member 6, and so on all around the periphery. When now the outer carrying members 3 are placed in rotation, for instance in the direction of 70 the arrow 8, they will describe a circle about the shaft 1. During this motion each separate wing surface will be extended and shortened, because each of the outer carrying members 3 are varying the distance from their corresponding inner carrying members 6 during their eccentric movement relatively to the latter and to the pivot 4. Each wing surface consequently will increase in 75 length from a minimum (at right in Figure 1) gradually into a maximum (at left in Figure 1) and then again decrease to minimum, and simultaneously with this varia- 80

It has been found that a simple construction can be obtained by constituting all wings by a portion of a common endless strap so arranged that for each wing surface the other carrying members are automatically regulating the strap length.

The invention is illustrated in an executive form in the annexed drawing, wherein Figure 1 shows the system proper diagrammatically. Figure 2 is a section on the line II—II of Figure 3 through the disc of the inner carrying members with adjacent parts. Figure 3 is a section on the plane III—III of Figure 2. Figure 4 shows a detail.

90 drawing, it will, when driven in the direction of arrow 8, bring about a buoyancy on the aeroplane dependent upon the size of the wing surface and the speed of rotation. It will also be seen that for each separate wing surface in its most effective propelling position (at left in Figure 1) the upper strap portion of the wing surface is travelling slowly inwards towards the pivot 4, whereas the lower strap portion is travelling slowly 95

1 is the driving shaft which is placed in a rapid rotation and carries a spider or rotor 2, the arms of which at their outer ends are provided with the outer carrying members 3. At some distance from the rotating shaft 1, but inside the circle described by the outer carrying members 3, there is arranged a pivot member 4 whereupon can rotate two discs 5 (only one shown in the drawing). Between these two discs there are fastened as many inner carrying members 6 as there are outer ones, and just in the same manner as the outer members 3 are regularly distributed on the circle they describe, the in- 45

outwards towards the carrying member 3. This motion of the strap has a favourable influence as regards the propelling action.

The carrying members 3 and 6 can also be adjusted in a somewhat inclined position relatively to the axis of rotation of shaft 1 whereby the wing surfaces obtain an angle to this axis. In this case the surfaces, besides producing a buoyancy as mentioned above, will also exert a propelling action in the direction of the axis of rotation, so that the apparatus may also operate partly as a fan. By suitable means the pivot 4 may be turned into different positions and fixed

therein relatively to shaft 1, so that the propelling or impulse direction of the apparatus can thereby be varied. In the position shown the impulse direction is vertically downwards. If the direction of rotation is reversed, the impulse direction will be vertically upwards. However, if pivot 4 is swung, for instance through 45° in the clockwise direction relatively to shaft 1, the impulse direction will make 45° with the vertical line etc. Thereby it is possible during the operation to change the propelling or impulse direction of the apparatus.

A constructional form of such an adjusting device is indicated in Figure 2, wherein on a hollow part of the driving shaft 1 two arms 9 are pivotally mounted (whereof only one is seen in the drawing). These arms do not take part of the rotation of shaft 1 and their hubs 10 can be adjusted by suitable means (not shown). In adjusted position the hubs 10 are held stationary by means of a solid shaft 15 projecting out through the said hollow part of driving shaft 1. Pivot 4 and discs 5 with the inner carrying members 6 are journalled in the outer ends of arms 9. Disc 5 is made bowl-shaped and into its peripheral part ball pivots 11 project. Said pivots are mounted on the end of shafts 12 of rolls 6. The inward movement of ball pivots 11 is limited by an inner disc 13 but in peripheral direction they are free to move in the annular channel formed between disc 13 and the outer flange of bowl-disc 5. However, between ball pivots 11 compression springs 14 are placed in the annular channel. In this manner ball pivots 11 will equalize the shocks which rolls 6 would otherwise be subjected to owing to the varying tensions in the different portions of strap 7 during the rotation.

As indicated diagrammatically in Figure 4 the outer carrying members 3 may also be radially yieldingly journalled in arms 2.

The carrying members may be so curved in the longitudinal direction (across to the distance between the said members) of the wing that the wing surface proper will take a correspondingly curved shape in this direction.

I claim as my invention:—

1. A propelling system comprising a driving shaft; a spider mounted on said shaft and having arms thereon, the outer end of each arm provided with a carrying member; a pivot member arranged in spaced relation from the shaft; a pair of spaced discs mounted on said pivot member and having inner carrying members mounted between the discs; and an endless strap arranged around the carrying members of the spider and the inner carrying members of the discs.

to form wings whereby rotation of the spider will cause the wings to vary periodically.

65

2. A propelling system comprising a driving shaft; a rotor mounted on said shaft and having carrying members thereon; a pivot member arranged in spaced relation from the shaft; a pair of spaced discs mounted on said pivot member and having inner carrying members mounted between the discs; and an endless strap arranged around the carrying members of the rotor and the inner carrying members of the discs to form wings whereby rotation of the rotor will cause the wings to vary periodically.

75

3. A propelling system comprising a driving shaft; a rotor mounted on said shaft and having carrying members thereon; an inner carrying member for each carrying member of the rotor; and an endless strap arranged around the carrying members of the rotor and the inner carrying members to form wings whereby rotation of the rotor will cause the wings to vary periodically.

80

4. A propelling system comprising a driving shaft; a rotor mounted on said shaft and having carrying members thereon; an inner carrying member for each carrying member of the rotor; and a strap arranged around the carrying members of the rotor and the inner carrying members to form wings whereby rotation of the rotor will cause the wings to vary periodically.

95

5. A propelling system comprising a driving shaft; a rotor mounted on said shaft and having carrying members thereon; an inner carrying member for each carrying member of the rotor; a strap arranged around the carrying members of the rotor and the inner carrying members to form wings whereby rotation of the rotor will cause the wings to vary periodically; and springs associated with said carrying members.

105

6. A propelling system comprising a driving shaft; a spider mounted on said shaft and having arms thereon, the outer end of each arm provided with a carrying member; a pivot member arranged in spaced relation from the shaft; a pair of spaced discs mounted on said pivot member and having inner carrying members mounted between the discs; an endless strap arranged around the carrying members of the spider and the inner carrying members of the discs to form wings whereby rotation of the spider will cause the wings to vary periodically; and springs associated with said carrying members.

110

In testimony whereof I have signed my name to this specification.

VICTOR THRANE.
